UNITED STATES PATENT OFFICE.

THOMAS W. SMITH AND CHARLES BIRELY, OF CONNERSVILLE, INDIANA.

MACHINE FOR FORMING FURNITURE-JOINTS.

SPECIFICATION forming part of Letters Patent No. 269,602, dated December 26, 1882.

Application filed June 3, 1882. (No model.)

To all whom it may concern:

Be it known that we, THOMAS W. SMITH and CHARLES BIRELY, citizens of the United States, residing at Connersville, in the county of Fayette and State of Indiana, have jointly invented certain new and useful Improvements in Furniture-Joints and Machines for Forming the Same, of which the following is a specification.

Our invention relates particularly to that class of furniture known as "drawer-work;" and it has for its object the construction of a new machine to rapidly and accurately form a peculiar joint for framing the carcass or shell that is to receive the drawers together.

The invention will be first fully described in connection with the accompanying drawings, and then the novel features particularly pointed out in the claims.

Figure 1 of the drawings is a side elevation of the frame and one end of our improved machine. The head-stock and opposite sliding bed or table is shown in central vertical section on line $x-x$ of Fig. 2. Fig. 2 is a vertical transverse section through line $y-y$ of Fig. 1, looking in the direction of the head-stock or center of the machine. Fig. 3 is an end elevation of the sliding bed-plate upon which the rails and stiles are held to be fed up to the bits. Fig. 4 is a longitudinal vertical section of one mandrel-carriers. Fig. 5 is a perspective view of the jointed portion of the stile. Fig. 6 is a similar view of the end of the cross-rail. Fig. 7 is an enlarged perspective view of the leading end of one of the sliding bed-plates, showing the arrangements for clamping the stuff to be jointed; and Fig. 8 is a similar view of one of the mandrel-frames.

A is the frame of the machine, which has standards A' projecting up from each side. Between these standards are mounted upon four cross-rods, c , any desired number of mandrel frames or carriers, C. In each of these frames are journaled two mandrels, B and D, which project out upon each end, the lower one, B, to receive upon each of its projecting ends a suitable cutting tool or clutch, b , to form the male portion of the joint upon the end of the rail, Fig. 6. The upper mandrel, D, is adapted to receive at each end bits d , for boring the edge of the stile, Fig. 5. The mandrel D passes through bosses d' , cast with or secured upon each end of the frame C. Within these bosses

are secured stationary tools d^2 of proper shape to cut part d^3 of the female joint upon the stile, Fig. 5. These mandrels are driven by a belt, 55 E, which passes over a pulley secured upon shaft F. The belt, after passing partly around all the pulleys upon the mandrels, is carried up and over a pulley journaled in a hanger secured over the center of a spring, G, which rests 60 in slots in the upper ends of standards A' . This arrangement for driving the mandrels is the same as that now usually employed to drive the spindles of the common boring-machine. The spindle-carriers C are adjustable 65 upon their rods c , and are held in any desired position by followers H on screw-threaded shafts which pass in front of the mandrel-frames and are secured in the standards A' , so that they may be brought closer together or 70 adjusted apart to suit the different kinds or sizes of drawers.

Upon each end of the frame A is arranged a sliding bed, I. These beds are sustained and guided to and from the cutters by two 75 rods, J, which pass from end to end of the frame upon each side. The rods pass through bosses I', secured to the under side of the sliding table or bed. The movement of the bed to and from the bits and cutters is controlled by cam-wheels K, secured upon the ends of a shaft which has its bearings in the cross-rods of frame A. The cam-shaft is driven by a belt, K', from a small pulley upon shaft F, which passes loosely over a large pulley upon the 85 cam-shaft. A friction-roller journaled upon one arm of a crank-lever, L, which is pivoted to lower cross-piece of frame A, tightens the belt K' and gives motion to the cam-shaft, when the treadle M, which actuates the crank-lever through rods $m m'$ and lever m^2 , is pressed down by the operator. The shaft is stopped by releasing the treadle from pressure. The cams work in slotted lugs k , which are secured to the under side of the bed I. 90

The stiles to be operated upon are held in a box, N, secured upon the front end of the sliding bed I. There is a fixed block, n , at one end of the box, through which a screw, n' , works to compress the stile between its inner 100 end and a centering-point in an adjustable block, n^2 , in the opposite end of the box N. A screw operated by a hand-wheel, n^3 , passes through a slot in the rear wall of box N and

the block n^2 , and is swiveled in a plate upon the opposite side. By this means the block n^2 is firmly held in any position within the limit of its movement, which is the slot in the back wall of the box N.

5 Back of the front end of the bed I is a box, O, which is transversely grooved down to the top of bed I to receive the ends of the rails, Fig. 6. Within the box O is a sliding bar, P, notched upon the upper edge to correspond with the transverse grooves in box O. This bar is moved longitudinally in the box O by a hand-screw, Q, which passes through a screw-threaded plate secured upon the end of 15 the box O, and is swivel-jointed to the end of the sliding notched bar P. In the position shown in Fig. 7, the ends of the bar-notches come even with the walls of the grooves in the box. In this position the ends of the bureau-rails will pass loosely into the grooves and notches; but a turn of the wheel Q will clamp the stiles firmly between one edge of 20 the sliding bar P and edge of the wall of the grooves in the box O. The machine shown 25 is adapted to form the joints for the stiles and cross-rails for the front of a three-drawer bureau, one of the upright side stiles being placed in each of the boxes N and four front rails in each of the boxes O, their outer ends 30 resting upon the bed I. The rails and stiles being clamped firmly in position, the operator presses down the treadle M and holds it down until the beds are advanced to the cutters and withdrawn again to the position shown in the 35 drawings, Fig. 1, which is performed by a single revolution of the cam-shaft.

It will be seen that when the front is put together the drawer-spaces will be the exact size in all the bureaus, and the drawer-fronts, 40 when dressed to a uniform size, will fit any bureau made by our process.

Of course the side walls of the part d^2 on the stile Fig. 5 provides the main support for the inside of the cross-rail, Fig. 6. It would therefore make little difference if the rounded portion of said joint were cut down, leaving a square-bottomed recess, except that the rounded portion closely fitting the concave portion of the rail end furnishes a good glue joint and 50 holds the parts much more firmly together than any joint not in use.

We have shown our machine with sliding beds and cutters arranged upon each side of the head-stock, thus making a double machine; but each half of the machine is complete 55 in itself, and one side can be used without the

other; and it is also plain that but one row of mandrels could be used, the bits b being used upon one end and the bits d d^2 upon the opposite end. In this case the box O should be 60 upon one of the sliding beds and the box N upon the other; but the arrangement shown in the drawings will insure better work with less labor.

What we claim as new, and desire to secure 65 by Letters Patent, is—

1. In a jointing-machine such as described, the combination of the frame having upwardly-projecting standards, the rods c, secured at their ends to the standards, the mandrel-frames 70 mounted on said rods and provided with bosses fitted with stationary cutters, the mandrels B D, provided with cutters, and the sliding bed.

2. In a machine of the character described, the combination, substantially as specified, of 75 frame A, standards A', rods c, and mandrel-frame C, with a screw rod or rods extending between the standards and screw-collars H to adjust and hold the said frames C upon their supports.

3. In a machine such as described, the combination, as specified, of a series of mandrels, B D, mounted to rotate one above the other, with sliding bed I, rods J J, cam K, lugs k, and suitable mechanism, as shown, to feed the bed 85 to and from the cutters.

4. The combination, substantially as hereinbefore set forth, of the sliding bed I, with clamping devices for holding the rails on the same, consisting of transversely-grooved box 90 O, notched rail P, adapted to slide within said box, and hand-screw Q to move the rod back and forth to clamp or release the rail ends.

5. In combination with the boring and mortising machine described, the sliding bed, the 95 clamping-boxes N O, secured one above the other upon the inner end of said bed, with suitable devices, such as described, to clamp and hold the stuff to be jointed, substantially as set forth.

100 6. The combination, substantially as specified, of the sliding beds I, cams K, treadle M, crank-lever L, and lever m^2 , with the connecting-rods $m m'$ to intermittently feed the beds to and from the cutters and readily arrest and stop the movement of the beds.

THOMAS W. SMITH.
